UNITED STATES PATENT OFFICE

ALFRED WEILAND, OF NESHANIC, NEW JERSEY, ASSIGNOR, BY MESNE ASSIGNMENTS, TO RADIO CORPORATION OF AMERICA, OF NEW YORK, N. Y., A CORPORATION OF DELAWARE

SOUND BOX SUPPORT AND USED NEEDLE RECEPTACLE

Application filed February 21, 1929. Serial No. 341,590.

My invention relates to a member or receptacle utilizable as a support for a sound reproducing device and/or a container or passage for the reception of used or worn talking machine or phonograph needles.

In accordance with my invention, a member of resilient material forms a support for a talking machine or phonograph sound reproducing device when it is moved from a position above the record supporting turntable; more particularly, said member of resilient material constitutes a receptacle for the reception of a part of said sound reproducing device.

Further in accordance with my invention, the aforesaid receptacle comprises a plurality of compartments, one receiving the aforesaid sound reproducing device and another receiving worn or used needles after disengagement from said device.

Further in accordance with my invention, the aforesaid receptacle is formed of suitable resilient material and is detachably carried by the motor board, or equivalent, of a talking machine or phonograph.

Further in accordance with my invention, the pivoted cover of a portable talking machine or phonograph positively retains the sound reproducing device thereof in engagement with a member of resilient material to prevent damage to the parts during transportation of said talking machine or phonograph.

My invention resides in the article, combination and features of construction of the character hereinafter described and claimed.

For an illustration of one of the forms my article or combination may take, reference is to be had to the accompanying drawings in which:

Figure 1 is a perspective view of a talking machine or phonograph having associated therewith a receptacle constructed in accordance with my invention.

Fig. 2 is a vertical sectional view, partly in elevation, of the device of Fig. 1 but with the casing cover in closed position.

Fig. 3 is a vertical sectional view, partly in elevation, taken at right angles to the showing of Fig. 2.

Fig. 4 is a perspective view of a combined sound box and used needle receptacle.

Fig. 5 is a bottom plan view of the receptacle of Fig. 4.

In accordance with my invention, there is provided a receptacle or member which receives or supports a sound reproducing device or instrumentality and which may comprise a chamber or passage for used or worn talking machine or phonograph needles. As illustrated herein, said receptacle or member is associated with a talking machine or phonograph of the portable type, although my invention is not to be limited to such portable mechanism.

As illustrative of one form of a portable talking machine or phonograph with which a receptacle or member constructed in accordance with my invention may thus be associated, there is shown a receptacle-like base A having a cover B pivoted or hinged thereto. As is usual in the art, said receptacle-like base A contains a motive device, not shown, together with suitable horn structure, not shown. Overlying the latter is a transverse member or motor board C supported, in the example shown, by the flanged section in which the side wall structure of the base A terminates.

As shown in Fig. 1, a turntable D overlies the motor board C which carries suitable structure E supporting a tone arm or taper tube F for oscillatory movement. The latter may terminate in the usual goose neck G which is pivoted thereto and which, at its otherwise free end, carries a sound reproducing device or instrumentality, as a sound box H of any desired type which comprises a diaphragm, not shown, adapted to be actuated by a needle arm or stylus bar I to which a needle or stylus J may be detachably secured by a clamping screw K, or equivalent. The tone arm or taper tube F, at its end adjacent its supporting structure E, discharges sound waves into the aforesaid horn structure by which said sound waves are amplified and from which they emerge through an opening in the aforesaid motor board C to the rear of the turntable D.

The aforesaid cover B may have pivoted

thereto a receptacle L receiving a plurality of talking machine or phonograph records M, movement of said receptacle L with respect to the cover B and elevation of the latter being controlled by a cam N with which coacts a member O carried by and movable with said receptacle L, all as more particularly described in the copending application of Herman Hollerith, Jr., Serial No. 303,418, filed 10 September 1, 1928.

A talking machine or phonograph of the character hereinafter described is portable, particularly in the sense that a plurality of records may be disposed or stored within the receptacle L and the cover B moved to and temporarily retained in closed position. To the end last named, there may be utilized suitable mechanism which is herein shown as comprising a member P carried by the front 20 wall of the base A and having pivoted thereto a latch Q coactable with a lug R carried by the cover B. Thus, with the cover B in closed position, the free end of the latch Q may be swung upwardly from the 25 position illustrated in Fig. 1 to thereby engage the lug R to temporarily lock said cover B in said closed position.

When thus transporting the talking machine or phonograph from place to place, it 30 is desirable that the aforesaid tone arm F and sound box H be restrained from movement interiorly of the closed casing; should this not be done, damage may result to some of the parts and particularly to the delicate 35 sound reproducing mechanism of the sound box.

In accordance with my invention, the aforesaid receptacle or member for receiving or supporting the sound reproducing device 40 H to thereby prevent undesired movement thereof may be and preferably is carried by the motor board C. If so, said motor board C may have or comprise a shallow, circular pocket or well formed by a member C1 depressed below the motor board level and forming with said motor board a circular ring 45 or flange C2. In said pocket or well, the aforesaid receptacle or member 1 is disposed, preferably in such manner as to be readily 50 or easily disengaged therefrom.

The receptacle or member 1, preferably, is circular in configuration and the lowermost end thereof, Figs. 2 and 3, comprises a circular bead or rim 2 by which the lower transverse section 3 of said receptacle 1 is spaced 55 from the member C1. The lower portion of receptacle 1, preferably, is of smaller diameter than the upper portion thereof and it is 60 this lower portion which is snugly received in the aforesaid pocket or well formed by member C1. As just stated, the upper portion of member 1 is of larger diameter than is the lower portion thereof and the surface 65 connecting said portions forms a circular de-

pression or ridge receiving the aforesaid circular ring or flange C2.

In the example illustrated, the member or receptacle 1 has or comprises two compartments or passages 4 and 5. The compartment 4 tapers somewhat and is adapted to receive the stylus J, one end of the stylus bar I and the lower part of the sound box proper, Fig. 2. As illustrated in Fig. 4, the cross-section of compartment 4 may resemble that of a half-circle, or a slightly larger portion of a circle. Said compartment 4 is bounded, in part by a substantially vertical wall 6, Figs. 3 and 4, and spaced therefrom is a tapered rib or projection 7 having a surface 8 substantially parallel with the aforesaid wall 6. One portion of the peripheral edge of the sound box H fits within the space defined by the wall 6 and surface 8; the distance therebetween, therefore, should correspond substantially 85 with the thickness of said peripheral edge of the sound box H.

The compartment or passage 5 is adapted as a container for used or worn needles after disengagement thereof from the stylus bar I. As illustrated particularly in Figs. 3 and 5, said used or worn needles are passed into the compartment 5 through an opening 9 in a transverse wall 10 forming the top or upper boundary of said compartment 5, the first needles thus deposited usually passing through the open lower end of compartment 5 and coming to rest upon the member C1, some of said needles, perhaps, finding their way beneath the transverse section 3 of the member 1. If 100 desired, the upper surface of wall 10 may be flared as well indicated in Fig. 4 to facilitate the passage of worn or used needles into the opening 9.

When desired, the member or receptacle 1 105 may readily be disengaged or removed from the well or compartment formed by the member C1. When thus disengaged, all of the used needles will be found upon said member C1 from which they may easily be removed.

The receptacle or member 1 usually is formed from resilient material, as cork or, and preferably, rubber of medium hardness. When constructed of such material, said receptacle or member 1, due to the action of 115 said resilient material, is snugly retained within the pocket or well formed by the member C1. Furthermore, when the sound box H is disposed within the compartment 4 of member 1, Fig. 2, before transporting the herein described talking machine or phonograph, the cover B may be brought to casing-closing position and the latch Q operated to temporarily lock said cover B in said position. Under such circumstances, particularly as illustrated in Figs. 2 and 3, the inner surface of the top wall of cover B contacts with the upper surface of the sound box H. As a 120 result, the latter is slightly depressed to 125 130

- thereby increase the pressure with which said sound box H engages the wall structure of the member 1. Since the latter, ordinarily, is constructed of resilient matter, as described above, the sound box H and tone arm F are temporarily retained in a fixed position within the closed casing and, therefore, the latter may be carried from place to place as desired without fear of damaging any of the parts.
- 10 If desired, a metallic ring 11 may circumscribe or enclose part of the wall structure of the member 1. This ring 11, to some extent, reinforces or supports said member or receptacle 1 although, usually, its purpose is little more than an ornamental one.
- 15 As herein illustrated, the member or receptacle 1 is an integral unit preferably molded from rubber. However, from some aspects of my invention, said member or receptacle 1 need not be integrally formed. Thus, under some circumstances, a resilient support for the sound box may be utilized in lieu of a compartment for a part thereof and, if desired, the sound box support or receptacle 25 may be separately formed and separately positioned from the container for the used or worn needles.
- 20 What I claim is:
1. In combination, a talking machine turntable, a swinging member, a sound reproducing device carried by said swinging member, and a member of resilient material forming a chamber in which a portion of said sound reproducing device is received when it is 30 swung to one side of said turntable.
2. In combination, a talking machine turntable, a movable member, a sound reproducing device carried by said movable member, and a member of resilient material forming a chamber in which a part of said sound reproducing device is housed when it is moved from a position above said turntable.
3. In combination, a casing, talking machine mechanism in said casing, a transverse member overlying said mechanism, a turntable overlying said transverse member, a movable member, a sound reproducing device carried by said movable member, and a cup member of resilient material carried by said transverse member and housing a part of said sound reproducing device when it is moved from a position above said turntable.
4. In combination, a casing, talking machine mechanism in said casing, a transverse member overlying said mechanism and having a pocket, a turntable overlying said transverse member, a movable member, a sound reproducing device carried by said movable member, and a cup member of resilient material received by the pocket of said transverse member and housing a part of said sound reproducing device when it is moved from a position above said turntable.
5. In combination, a casing, a pivoted cover therefor, talking machine mechanism in
- said casing, a transverse member overlying said mechanism, a turntable overlying said transverse member, a swinging member, a sound reproducing device carried by said swinging member, and a member of resilient material carried by said transverse member and forming a chamber in which a part of said sound reproducing device is housed when it is swung to one side of said turntable, said cover, when in casing-closing position, increasing the pressure with which said sound reproducing device engages said member of resilient material.
6. In combination, a casing, a pivoted cover therefor, talking machine mechanism in said casing, a transverse member overlying said mechanism, a turntable overlying said transverse member, a movable member, a sound reproducing device carried by said movable member, a member of resilient material forming a chamber in which a part of said sound reproducing device is received when it is moved from a position above said turntable, said cover, when in casing-closing position, increasing the pressure with which said sound reproducing device engages said member of resilient material, and latch mechanism for retaining said cover in said casing-closing position.
7. In combination, a talking machine turntable, a movable member, a sound reproducing device carried by said movable member and having a sound reproducing needle readily disengageable therefrom when worn by contact with a turntable-supported talking machine record, and a member forming a receiving-passage for worn needles and a housing for a part of said sound reproducing device when it is moved from a position above said turntable.
8. In combination, a talking machine turntable, a movable member, a sound reproducing device carried by said movable member and having a sound reproducing needle readily disengageable therefrom when worn by contact, with a turntable-supported talking machine record, and a member of resilient material forming a receiving-passage for worn needles and a chamber receiving a part of said sound reproducing device when it is moved from a position above said turntable.
9. In combination, a casing, talking machine mechanism in said casing, a transverse member overlying said mechanism, a turntable overlying said transverse member, a movable member, a sound reproducing device carried by said movable member and having a sound reproducing needle readily disengageable therefrom when worn by contact with a turntable-supported talking machine record, and a member of resilient material carried by said transverse member and forming a receiving-passage for worn needles, said member of resilient material forming a receptacle in which a part of said sound re-

producing device is received when it is moved from a position above said turntable.

10. In combination, a casing, a pivoted cover therefor, a talking machine mechanism 5 in said casing, a transverse member overlying said mechanism, a turntable overlying said transverse member, a movable member, a sound reproducing device carried by said movable member and having a sound reproducing needle readily disengageable therefrom when worn by contact with a turntable-supported talking machine record, and a member of resilient material carried by said transverse member and forming a receiving- 15 passage for worn needles, said member of resilient material forming a receptacle in which a part of said sound reproducing device is received when it is moved from a position above said turntable, said cover, when 20 in casing-closing position, increasing the pressure with which said sound reproducing device engages said member of resilient material.

11. The combination with a member of 25 a talking machine, of a receptacle carried by said member and comprising a plurality of compartments, one of said compartments receiving a part of the sound reproducing device of said talking machine, another of 30 said compartments forming a receiving-passage for worn needles after disengagement thereof from said sound reproducing device.

12. The combination with a member of a talking machine, of a receptacle carried by 35 said member and readily disengageable therefrom, said receptacle comprising a plurality of compartments, one of said compartments receiving a part of the sound reproducing device of said talking machine, another of 40 said compartments forming a receiving-passage for worn needles after disengagement thereof from said sound reproducing device.

13. The combination with a member of a 45 talking machine, of a receptacle of resilient material carried by said member and comprising a plurality of compartments, one of said compartments receiving a part of the sound reproducing device of said talking machine, another of 50 said compartments forming a receiving-passage for worn needles after disengagement thereof from said sound reproducing device.

14. The combination with a member of a 55 talking machine, of a molded receptacle of rubber having medium hardness carried by said member and comprising a plurality of compartments, one of said compartments receiving a part of the sound reproducing device 60 vice of said talking machine, another of said compartments forming a receiving-passage for worn needles after disengagement thereof from said sound reproducing device.

15. The combination with the motor board 65 of a talking machine, of a receptacle of re-

silient material carried by said motor board, said receptacle comprising a plurality of compartments, one of said compartments receiving a part of the sound reproducing device of said talking machine, another of said compartments forming a receiving-passage for worn needles after disengagement from said sound reproducing device. 70

16. The combination with the motor board 75 of a talking machine, of a receptacle of resilient material carried by said motor board and readily detachable therefrom, said receptacle comprising a plurality of compartments, one of said compartments receiving a part of the sound reproducing device of said talking machine, another of said compartments forming a receiving-passage for worn needles after disengagement from said sound reproducing device. 80

17. The combination with the motor board 85 of a talking machine, of a receptacle of resilient material carried by said motor board, said receptacle comprising a plurality of compartments, one of said compartments being open at its top and receiving a part of the 90 sound reproducing device of said talking machine, another of said compartments being open at its bottom and forming a receiving-passage for worn needles after disengagement from said sound reproducing device. 95

18. In combination, a casing, a pivoted cover therefor, phonograph mechanism in said casing, a transverse member overlying said mechanism, a turntable overlying said transverse member, a sound reproducing device carried by said movable member, a resilient receptacle supported by said transverse member and adapted to accommodate said reproducing device in non-operative position, said receptacle being so relatively disposed with respect to the walls of said casing that when said reproducing device rests in said receptacle and said cover is moved toward closed position, the said receptacle and reproducing device are positively urged into 110 closer contact.

19. As an article of manufacture, a combined phonograph-reproducer support and used needle container of resilient material.

20. As an article of manufacture, a cup- 115 shape element of resilient material, said element having a plurality of compartments, one of said compartments being adapted to support a phonograph pick-up device and the other of said compartments being adapted to receive phonograph needles. 120

21. In combination, a vertically disposed pivot member, a supporting arm mounted thereon and adapted to swing in a horizontal plane, a sound reproducing device pivotally 125 carried by said arm for swinging movement in the plane of said pivot member, a receptacle adapted to partially receive said reproducing device, and means whereby said device when partially received by said receptacle, 130

- is subjected to pressure tending to urge it in the plane of said pivot member further into said receptacle. 22. In a phonograph, a sound reproducing device, a casing, a resilient receptacle supported within said casing and adapted to accommodate said device, and a pivoted cover for said casing, said receptacle being so relatively disposed with respect to the walls of said casing that, when said reproducing device rests in said receptacle, and the cover is moved toward closed position, the receptacle and reproducing device are positively urged into closer contact. 23. In a phonograph, the combination of a motor board, a vertically disposed pivot member carried by said motor board, a supporting arm mounted thereon and adapted to swing in a horizontal plane, a sound reproducing device pivotally carried by said arm for movement in the plane of said pivot member, a receptacle of resilient material adapted to partly receive said reproducing device therein, and means whereby said device, when partially received by said receptacle, is subjected to pressure tending to urge it in the plane of said pivot member further into said receptacle. 24. In combination, a vertically disposed pivot member, a supporting arm mounted thereon and adapted to swing in a horizontal plane, a sound reproducing device pivotally carried by said arm for swinging movement in the plane of said pivot member, a receptacle adapted to accommodate said reproducing device, and means whereby said device when accommodated by said receptacle, is subjected to pressure tending to urge it in the plane of said pivot member into a closer contact with said receptacle. 25. In a phonograph the combination of a vertically disposed pivot member, a supporting arm mounted thereon and adapted to swing in a horizontal plane, a sound reproducing device pivotally carried by said arm for swinging movement in the plane of said pivot member, a receptacle of resilient material adapted to partially receive said reproducing device therein, and means whereby said device when partially received by said receptacle, is subjected to pressure tending to urge it in the plane of said pivot member further into said receptacle. 26. In combination, a phonograph, a recess formed therein, a cup-shape element of resilient material adapted to be detachably held in said recess, said cup-shape element having a plurality of compartments, one of said compartments being adapted to receive a sound reproducing device in non-playing position, the other of said compartments being closed by the seating of said element in said recess to provide a receptacle for used phonograph needles. 27. In combination, a phonograph, a cup-shaped element of resilient material, and a recess adapted to detachably receive said element formed in said phonograph, said cup-shaped element having a plurality of compartments, one of said compartments being adapted to receive a sound reproducing device in non-playing position, the other of said compartments being closed by the seating of said element in said recess to provide a receptacle for used phonograph needles. 28. In combination, a phonograph, a recess formed therein, a cup-shape element of resilient material adapted to be detachably seated in said recess, said cup-shape element having a plurality of compartments, one of said compartments being adapted to receive a sound reproducing device in non-playing position, the other of said compartments being closed by the co-operation of said element with the bottom surface of said recess when seated therein, to provide a receptacle for used phonograph needles. In testimony whereof I have signed this specification this 20th day of February, 1929. ALFRED WEILAND.
